Primary Examiner — Mary Ann Calabrese

(57) **CLAIM**

We claim the ornamental design for a table, as shown and described.

DESCRIPTION

FIG. 1 is a front perspective view of a table, showing our new design;

FIG. 2 is a bottom perspective view of the table thereof;

FIG. 3 is a front view of the table thereof;

FIG. 4 is a right side view of the table thereof, the left side view is a mirror image of the right side view of FIG. 4;

FIG. 5 is a top view of the table thereof; and,

FIG. 6 is a bottom view of the table thereof.

The broken lines in the drawings illustrate portions of the table that form no part of the claimed design.

1 Claim, 3 Drawing Sheets
